UNITED STATES PATENT OFFICE.

HARRY C. FRICKE AND GEORGE E. TURNER, OF PITTSBURG, PENNSYLVANIA, ASSIGNORS TO TURNER-FRICKE MANUFACTURING COMPANY, OF PITTSBURG, PENNSYLVANIA.

ADMISSION-VALVE FOR EXPLOSIVE-ENGINES.

No. 873,534.

Specification of Letters Patent.

Patented Dec. 10, 1907.

Application filed August 30, 1907. Serial No. 390,772.

To all whom it may concern:

Be it known that we, HARRY C. FRICKE and GEORGE E. TURNER, citizens of the United States, residing at Pittsburg, in the 5 county of Allegheny and State of Pennsylvania, have invented certain new and useful Improvements in Admission-Valves for Explosive-Engines; and we do hereby declare the following to be a full, clear, and exact 10 description of the invention, such as will enable others skilled in the art to which it appertains to make and use the same.

Our invention consists in the novel features hereinafter described reference being 15 had to the accompanying drawings which illustrate one form in which we have contemplated embodying our invention and said invention is fully disclosed in the following description and claims.

20 In the operation of gas or explosive engines, particularly those having two or more cylinders, it is often desirable to throw out of operation the inlet valve, of one or more cylinders, as for example when the engine is to be started by means of compressed air applied to one or more cylinders, and also when it is desired to remove and replace an igniter plug while the engine is running, or for throwing out of operation one or more cylinders of 30 a multicylinder engine when running on a very light load, etc.

Our invention consists in making the inlet valve operating rod or stem in separate parts, which is in itself desirable as it enables 35 the valve to be operated in a perfectly straight line, without any lateral strain, or twist with respect to its seat, and we provide one part of the valve rod with a pivoted portion, which can be locked rigidly in operative 40 position in line with the other parts of the rod, to operate the valve, and which can be released and thrown out of line when desired so as to disconnect the valve and the operating mechanism therefor, when desired.

45 While the invention is particularly applicable to the inlet valves of explosive engines, it may be used for other purposes if desired or found convenient.

In the drawings, Figure 1 is a partial sectional view of an explosive engine, taken 50 through the cylinder, piston and a portion of the crank case on the inlet side of the engine, and illustrating our invention applied thereto. Fig. 2 is an enlarged view partly in sec-

tion of a portion of the valve actuating rod. 55 Fig. 3 is an enlarged view partly in section showing the hinge or pivotal joint of the movable rod section. Fig. 4 is a horizontal section on line 4—4 of Fig. 2.

In the drawings A represents the crank 60 case or base, of an explosive engine which may have one, two or more cylinders, only one of which shows in the section view. B represents the cylinder, C the piston, D the piston rod, all of which may be of any preferred construction.

F represents the inlet passage for the explosive mixture and F' represents the inlet valve, fitting a seat f in said passage. The valve F' is provided with a stem f' passing 70 through a suitable bearing and having a collar f² adjustably secured on its lower end, between which and the bearing is a coiled spring f³, which keeps the valve F' normally seated.

Below the valve stem f' and normally in line therewith is the inlet valve operating rod, preferably formed in two parts f⁴, f⁵ pivotally connected or hinged together. The lower end of part f⁵ screws into a yoke f⁶ 80 pivotally connected by a pin f⁷ to a horizontal yoke on the end of an arm f⁸ which is pivoted to a stationary part of the base. The pin f⁷ also carries a friction roller f⁹ which engages the inlet cam h on the inlet cam 85 shaft H, said shaft being driven by gearing from the crank shaft at half the speed of the crank shaft, as is usual in engines of the four cycle type.

The part f⁵ of the valve rod, extends 90 through a collar I, secured to the exterior of the crank case, and provided with a guiding aperture for the passage of the rod. The upper part f⁴ of the valve rod is hinged to the part f⁵ by a pivot pin f¹⁰ as shown in the drawings, so as to permit the part f⁴ to swing outwardly or inwardly, or laterally as preferred, a sufficient distance to disengage the valve stem f' which is in line with the part f⁵ of the valve rod, and we prefer to form said hinge, so as to permit the part f⁴ to swing off to an angle of 90° as shown in dotted lines Fig. 1, although that is not essential.

In order to hold the hinged part f⁴ in operative position, that is in line with the valve 105 stem f' and lower part f⁵ of the valve rod, we provide a locking sleeve G which surrounds portions of the parts f⁴, f⁵ adjacent

to their pivotal connection as shown in full lines in Fig. 1 and normally rests on a shoulder or stop f^{11} provided on the lower part f^5 of the valve rod to limit the downward movement of the locking sleeve. The upper part of the rod is made longer than the sleeve G, and is of sufficient length to permit the sleeve to be raised thereon so as to disengage the hinge joint, and permit the part f^4 to be 10 swung out of line with the valve stem f' and the lower part f^5 of the valve rod, thus disconnecting the valve F' from its operating mechanism as indicated in dotted lines in Fig. 1. The part f^4 is provided with a shoulder or enlargement or other device as indicated at f^{12} to form a stop to limit the upward movement of the collar G and prevent it from jarring off and becoming lost when the part f^4 is thrown into inoperative position.

When the part f^4 is thrown out of operative position as shown in dotted lines Fig. 1, it will remain in such position by gravity and the weight of the sleeve G will assist in holding it in such inoperative position. The action of the cam on the lower part of the rod is not disturbed and the valve can be instantly brought into operation by simply rocking the hinged part f^4 into vertical position, in line with the part f^5 and the valve stem, when the sleeve G will fall over the hinged portions of the parts f^4 f^5 and lock the parts rigidly.

When the part f^4 of the rod is in operative position, it is obvious that the cam h will elevate the valve F, and as the valve stem f' , which forms a part of the valve rod is separate from the parts f^4 f^5 , it is obvious that the valve will seat itself accurately under the action of its retracting spring f^3 after each operation of the valve, and any lateral motion of the valve rod parts f^4 f^5 will not be imparted to the valve.

What we claim and desire to secure by Letters Patent is:—

1. In an explosive engine, the combination with a valve and its seat, and a valve actuating cam, of a valve rod interposed between the valve, and cam, said rod having a hinged part capable of being swung out of line with other portions of the rod, and a locking de-

vice for holding said hinged part rigidly in operative position, substantially as described.

2. In an explosive engine, the combination with a valve and its seat, and a valve actuating cam, of a valve rod interposed between the valve, and cam, said rod having a hinged part capable of being swung out of line with other portions of the rod, and a locking device surrounding portions of said rod adjacent the said hinge connection, for holding said hinged part in operative position, said locking device being movable longitudinally on said rod, to release said hinged portion, substantially as described. 65

3. In an explosive engine, the combination with a valve and its seat, and a valve actuating cam, of a valve rod interposed between the valve, and cam, said rod having a hinged part capable of being swung out of line with other portions of the rod, a locking sleeve on said rod, adapted to engage portions thereof adjacent to said hinge connection, for holding said hinged part in operative position, and means for holding said sleeve in its operative position, substantially as described. 75

4. In an explosive engine, the combination with a valve and its seat, and a valve actuating cam, of a valve rod interposed between the valve, and cam, said rod having a hinged part capable of being swung out of line with other portions of the rod, and a gravity locking device having a sliding engagement with said rod and provided with portions adapted to surround the rod adjacent to its hinge connection, substantially as described. 85

5. In an explosive engine, the combination with a valve and its seat, and a valve actuating cam, of a valve rod interposed between the valve, and cam, said rod having a hinged part capable of being swung out of line with other portions of the rod, a locking sleeve on said hinged portion, and stops for limiting the movement of said sleeve, substantially as described. 90

In testimony whereof we affix our signatures, in the presence of two witnesses.

HARRY C. FRICKE.
GEORGE E. TURNER.
